CARPORT

Jack A. Smithhart, Garland, Tex., assignor to Continental Steel Company, Garland, Tex.

Filed Sept. 4, 1969, Ser. No. 19,015

Term of patent 14 years

Int. Cl. D25—03

U.S. Cl. D13—1

Fig.1

Fig.2

Fig.3

Fig.4

FIG. 1 is a front view in perspective of a carport of my new design taken from slightly above the roof toward one end;

FIG. 2 is a front perspective view similar to FIG. 1, taken from slightly below the roof toward the opposite end;

FIG. 3 is a front view in elevation of the carport; and

FIG. 4 is an end view in elevation of the carport.

The concrete cylinders shown in broken lines in the several views are disclosed for illustrative purposes only and form no part of the claimed design.

I claim:

The ornamental design for a carport, substantially as shown and described.
